UNITED STATES PATENT OFFICE.

CHARLES AUTH, OF NEW YORK, N. Y., ASSIGNOR TO EMMA LOUISE AUTH, OF BROOKLYN, NEW YORK.

ANNUNCIATOR-DROP.

1,142,477.

Specification of Letters Patent. Patented June 8, 1915.

Application filed December 29, 1908. Serial No. 469,900.

To all whom it may concern:

Be it known that I, CHARLES AUTH, of New York, in the county of New York, and in the State of New York, have invented a certain new and useful Improvement in Annunciator-Drops, and do hereby declare that the following is a full, clear, and exact description thereof.

My invention relates to an improvement in annunciator drops, and especially drops such as those shown and described in my application, Serial No. 442,396, filed July 7th, 1908.

The object of my invention is to construct an annunciator drop of the above character which will be applicable with advantage to structures which are subjected to considerable movement or vibration, as ships, elevators, movable partitions, etc. In such structures it is necessary to make use of a drop which will be maintained permanently and positively in any position in which it is set, as the constant motion or vibration has a continual tendency to dislodge the indicator which has been set in any one position. In indicators which depend merely upon gravity or some mechanical construction for maintaining the parts in their adjusted position, I find that there is a great tendency to rebound from the adjusted position into the original position from which the parts have been moved.

In my present invention I have accomplished the purpose above referred to, and have at the same time avoided other disadvantages which are present in certain instances in preceding constructions.

For the purpose of maintaining the drop in any one adjusted position, I make use of a permanent magnet, so that the armature to which the signalling device of the drop is attached, is continually maintained in a magnetized field. This arrangement causes the armature to be attracted by the permanent magnet to any one adjusted position when the circuit is broken, as well as when the circuit is closed. I have further arranged this permanent magnet in such a way that one end of it is attached to the cores of the electro-magnets which I make use of for changing the armature from one position to another. Because of this construction, when the circuit is broken the cores of the electro-magnets form a horseshoe magnet with the permanent magnet,

so that in any one position of the armature one end is attracted by the permanent magnet and the other end is attracted by the core of one of the electro-magnets which it overlies and which has been magnetized by induction from the permanent magnet. When the circuit is broken, therefore, both ends of the armature are positively attracted by some portion of the magnet so as to maintain the armature in its adjusted position.

In order to effect the change of armature from one position to another, I make use of two electro-magnets so wound that the closing of the signaling circuit will cause one electro-magnet to attract one end of the armature and the other to repel the other end of the armature, while the closing of the re-setting circuit will effect the reverse magnetization of the two electro-magnets. This produces a very powerful actuation of the armature with a given voltage, actual practice having shown that the indicator can be moved with a very much smaller voltage in this arrangement than in one where dependence is merely had upon a single attracting electro-magnet and the influence of gravity. I make the permanent magnet of sufficient size to prevent any erroneous manipulations of the circuits from de-magnetizing it.

A further feature of my invention consists in that all the parts of the annunciator drop are attached to one another in a simple manner, so that the apparatus is entirely self-contained and requires no adjustment other than its initial installation.

I have shown one form of my invention in the accompanying drawings, in which— Figure 1 is an elevation of the annunciator drop; Fig. 2 is a plan view thereof; Fig. 3 is a diagrammatic view showing the armature in one position; Fig. 4 is a view similar to Fig. 3, showing the parts in the other position; Fig. 5 is a view of a non-conducting plate situated on the front of the solenoids shown in section; Fig. 6 is a front elevation of the plate through which the signal appears; Fig. 7 is a diagrammatic view of the circuits employed.

In the drawings, 1 and 2 are a pair of electro-magnets which are attached to one another at their bases by means of a soft-iron angle plate 3. Each electro-magnet is provided with an inner and an outer wind-

ing, the electro-magnet 1 having the inner winding 3 and the outer winding 4, and the electro-magnet 2 having the inner winding 5 and the outer winding 6. The outer winding 6 and the inner winding 3 are located in a circuit which may be called the signaling circuit, which is adapted when closed to operate the signal to attract the attention of the attendant. The inner winding 5 and the outer winding 4 are situated in another circuit, which may be called the re-setting circuit and which is adapted when closed to re-set the indicating device. In practice, these two circuits are arranged with one common conductor throughout a portion of the two circuits at 7. In operation, the outer windings 4 and 6 operate as the repelling windings, and the inner windings 3 and 5 as the attracting windings.

For reasons to be hereinafter described, I make the attracting windings of a higher resistance than the repelling windings, and I also make the total resistance through the entire re-setting circuit greater than the resistance in the signaling circuit.

Attached to one angle of the angle plate 3, there is a laminated permanent magnet 8, which is screwed upon the angle plate 3 by means of a screw 9. The magnet 8 extends in a direction parallel with the electro-magnets 1 and 2, and projects slightly beyond the coils thereof ending in a plane substantially that of the cores 9^a of the solenoids. A non-magnetic plate 10 extends over the front surfaces of the electro-magnets. This plate 10 has two lateral guides 11 which maintain the front ends of the permanent magnet 8 in place. At one side of the electro-magnets the plate 10 is provided with two reversely directed projections 12 which act as stops for the ends of an armature 13 which is pivoted upon a pintle 14 supported at one end in the plate 10 and at the other end in an extension 15 of the said plate which is located parallel to the first-mentioned portion of the plate. The extension 15 is provided with a plurality of holes, in this case substantially in the shape of the arms of a Maltese cross. In the rear of the extension 15 there is supported, upon the pintle 14 in front of the armature 13, a disk 16 carrying a device of some description which may be made to show through the apertures 15^a in the extension.

In the operation of the device, it is assumed that the parts are re-set in such a position that the disk 16 does not disclose its distinguishing marks through the apertures 15^a of the plate 15, and that the armature 13 is situated so that one end thereof overlies the electro-magnet 2, while the other end is attracted by the permanent magnet 8. If now the signaling circuit which includes the windings 3 and 6 is closed, the armature will be moved to the

other position in which one end thereof overlies the electro-magnet 1, while the other end overlies the permanent magnet 8. This will cause the distinguishing marks appearing upon the disk 16 to appear 70 through the apertures 15^a in the disk 15. In order to re-set the device, it is merely necessary to close the re-setting circuit including the windings 4 and 5 which will move the armature and the disk back to 75 their original positions.

While the circuit is broken and the parts are in the normal re-set position, inasmuch as the permanent magnet is connected by means of an iron plate with the cores of the 80 solenoids, the said cores and the permanent magnet will act as a horse-shoe magnet, so that each end of the soft iron armature is attracted thereby, one end being attracted by the permanent magnet and the other end 85 by the core of the electro-magnet which it overlies. When now the signaling circuit is closed the inner winding of the electro-magnet is caused to attract one end of the armature 13, and the outer winding of the electro-magnet 2 is caused to repel the other end 90 of the armature. This results from the fact that when the circuit is so closed, the electro-magnet 1 produces a minus magnetism at the front end of the core, while the electro-magnet 2 produces a plus magnetism at the front end of its core. Because of the 95 presence of the strong permanent magnet 8, the armature is itself always magnetized by induction and the end of the armature which is turned away from the permanent magnet will have the same polarity. The front end of the permanent magnet being plus, the end of the armature turned away from it would 100 be plus. The end turned away from the magnet 8 would, therefore, be repelled by electromagnet 2 when the signaling circuit is closed as above. Upon the consequent shifting of the armature, the other pole would become plus and would be attracted 105 by electromagnet 1, which is minus. This position is shown in Fig. 4. Such being the case, it will be seen that when the armature has assumed its position as a result of the closing of the signaling circuit, both ends 110 of the armature will be attracted by the portions of the actuating magnet which they overlie. It will be understood that the armature is attracted in this manner by the horse-shoe magnet formed by the permanent 115 magnet and the cores of the electro-magnets. The same reasoning applies to the movement of the parts when the re-setting circuit is closed, the poles of the armature and electromagnets, however, being reversed.

In order to cause the magnetism produced by the two electro-magnets at the closed position of either circuit to be approximately equal and thus to neutralize the effect of each other upon the permanent magnet, I 130

make the attractive windings longer than the repellent windings by giving them more turns, thus making the attractive magnetism greater in any one circuit than the repellent magnetism. This is necessary in order that the flux passing through the attractive coil may be made equal to the flux passing through the repellent coil, since the reluctance of the magnetic circuit through the core of the repellent coil, the armature and the permanent magnet, would be less than through the corresponding path through the core of the attractive coil, due to the fact that before operation the armature overlies the repellent coil. When so arranged, the magnetism in the attractive coil is substantially equal to the reverse magnetism produced in the other electromagnet by the repellent coil thrown in circuit simultaneously therewith. As a result, the de-magnetization produced upon the permanent magnet, because of the magnetization of the repellent coil, is neutralized substantially by the magnetizing effect of the attractive coil upon the permanent magnet. I, however, make the total length of windings, that is to say the number of turns, of the re-setting coils greater than the total length of windings or number of turns of the signaling coils, inasmuch as it is usual to place a number of drops in a single circuit for re-setting purposes, whereas it is usual to place only a single drop in a signaling circuit. In the case where the re-setting and signaling currents are of equal voltage, the length of windings to which I have referred above will produce substantially the same effect upon any one annunciator drop, when the re-setting circuit is closed and when the signaling circuit is closed.

At the same time, although, the length of windings or number of turns in the attractive coil of the resetting circuit is greater than the length of windings or number of turns of the repellent coil in the same circuit and the length of windings or number of turns of the attractive coil in the signaling circuit is greater than the length of windings or number of turns of the repellent coil in the same circuit, and, although, the length of windings or number of turns of the first mentioned attractive coil is greater than that of the other attractive coil and the length of windings or number of turns of the first mentioned repellent coil is greater than that of the other repellent coil, as above described, still the difference in the length of windings or number of turns of the attractive and repellent coils respectively of the two circuits are substantially equal as the effects of the attractive and repellent coils upon the permanent magnet should neutralize each other in each circuit.

While I have described my invention above in detail, I wish it to be understood

that I am not necessarily limited thereby, but consider that my invention is a broad one and capable of many modifications and applications, without departing from the spirit thereof.

I claim:

1. In a device of the character described, the combination of an armature for operating a signal, separate electro-magnetic devices for operating upon different portions of the armature, each said device having a plurality of windings repellent and attractive to the armature severally, and means for establishing a circuit simultaneously through a repellent winding of one electro-magnetic device and an attractive winding of the other.

2. In a device of the character described, an electro-magnetic device for operating a signal, said device being provided with opposite windings capable of reversing the polarity of the said device to operate the signal in different directions and means for throwing into a circuit the windings running in one direction only at a given time.

3. In a device of the character described, an armature for operating a signal, separate electro-magnetic devices for operating upon different portions of the armature, each said electro-magnetic device having a plurality of windings repellent and attractive to the armature severally, the repellent windings having fewer turns than the attractive windings, and means for establishing a circuit simultaneously through a repellent winding of one said device and an attractive winding of the other.

4. In a device of the character described, an armature, a repellent electro-magnetic device for operating upon one portion thereof, an attractive electro-magnetic device for operating upon another portion thereof, said devices having cores, and another magnetic device for operating upon the armature connected to the cores of the electro-magnetic devices, said repellent electro-magnetic device having a smaller magnetic force than the attractive electro-magnetic device.

5. In a device of the character described, an armature, a repellent electro-magnetic device for operating upon one portion thereof, an attractive electro-magnetic device for operating upon another portion thereof, said devices having cores, and a permanent magnet for operating upon the armature connected to the cores of the electro-magnetic devices, said repellent electro-magnetic device having a smaller magnetic force than the attractive electro-magnetic device.

6. In a device of the character described, a signal, an electro-magnetic device for resetting the same, and another electro-magnetic device for throwing the signal into operation, the windings of the resetting electro-magnetic device having more turns than

the windings of the other electro-magnetic device, only one of said electromagnetic devices being thrown into circuit at a given time.

7. In a device of the character described, the combination of an armature for operating a signal, an electro-magnet for operating upon one portion of the armature, another electro-magnet for operating upon another portion of the armature, each said electromagnet having opposite windings to repel or attract the armature, a repellent winding of one electro-magnet and an attractive winding of the other electro-magnet being located in a circuit for resetting the signal, and an attractive winding of the first mentioned electro-magnet and a repellent winding of the last mentioned electro-magnet, being located in another circuit for operating the signal, the number of turns of the windings in any one circuit being different and the difference between the number of turns of the repellent and the attractive windings of one circuit being equal to that in the other circuit.
8. In a device of the character described, the combination of an armature for operating a signal, an electro-magnet for operating upon one portion of the armature, another electro-magnet for operating upon another portion of the armature, each said electromagnet having opposite windings to repel or attract the armature, a repellent winding of one electro-magnet and an attractive

winding of the other electro-magnet being located in a circuit for resetting the signal, and an attractive winding of the first mentioned electro-magnet and a repellent winding of the last mentioned electro-magnet being located in another circuit for operating the signal, the lengths of the windings in any one circuit being different, the difference between the lengths of the repellent and the attractive windings of one circuit being equal to that in the other circuit, and the length of the windings of the resetting circuit being greater than the length of the windings of the circuit for operating the signal.

9. In a device of the character described the combination of a soft-iron armature for operating a signal, a separate electro-magnetic device for operating each end of the armature, and means for passing a current simultaneously through both electro-magnetic devices to move the armature from one position to another, to cause one electro-magnetic device to repel the corresponding end of the armature and the other electro-magnetic device to simultaneously attract the other end of the armature.

In testimony that I claim the foregoing I have hereunto set my hand.

CHARLES AUTH.
